UNITED STATES PATENT OFFICE.

JONAS THEODOR LAGERGREN, OF TORONTO, ONTARIO, CANADA.

WATER-PURIFIER FOR ICE-MAKING.

1,211,184.

Specification of Letters Patent.

Patented Jan. 2, 1917.

Application filed December 3, 1915. Serial No. 64,894.

To all whom it may concern:

Be it known that I, JONAS THEODOR LAGERGREN, of the city of Toronto, in the county of York, in the Province of Ontario, Canada, have invented certain new and useful Improvements in Water-Purifiers for Ice-Making, for a type of which the following is the specification.

My invention relates to improvements in water purifiers for ice making machines and the object of my invention is to provide means for preventing ice having a cloudy appearance caused by air, gases and other foreign matter contained in the water before freezing, and it consists essentially of a container, filtering material therein through which the water passes, an overflow, means for breaking up the overflow into fine portions, a vacuum pipe connected to the container, and a receiving tank connected to the container and to the vacuum pipe.

Figure 1 is a cross-section through my device. Fig. 2 is an enlarged plan view of a fragmentary portion of my device for breaking up the overflow, the top being removed and the container shown in cross-section. Fig. 3 is an enlarged view of a fragmentary portion of Fig. 1. Fig. 4 is an enlarged plan view of a fragmentary portion of an alternative form of my device shown in Fig. 2, the top being removed and the container shown in cross section.

In the drawings, like letters of reference indicate corresponding parts in each figure. 1 indicates a pipe leading from the source of supply. 2 indicates a stop cock in the pipe 1. 3 indicates a container having a reduced lower portion forming a ledge 3^x. 4 indicates the cover of the container 3 held in place by bolts 4^x and nuts 5. 6 indicates packing between the container 3 and the cover 4.

7 indicates a pipe leading from the container 3 to a vacuum pump (not shown). 8 indicates a 3-way cock in the pipe 7. 9 indicates a container within the container 3. 10 indicates a cylinder within the container 9, held out of contact with the bottom of container 9 by the angles 11. 12 indicates a cylinder contained within the cylinder 10 and having a flange 13 secured to the bottom of container 9.

14 indicates a cylinder within the cylinder 12 held out of contact with the bottom of container 9 by the angles 15.

16 indicates a cylinder contained within the cylinder 14 and having a flange 17 secured to the bottom of container 9. 60

18 indicates a cylinder contained within the cylinder 16 and held out of contact with the bottom of the container 9 by the angles 19.

20 indicates filter material contained in 65 the interior of the cylinders 18, 16, 14, 12, 10 and 9.

21 indicates an annular tray secured to the exterior of the cylinder 16.

22 indicates holes in the bottom of the 70 tray 21.

23 indicates an annular tray secured to the exterior of the cylinder 12.

24 indicates holes in the bottom of the 75 tray 23.

25 indicates an annular tray secured to the cylinder 9.

26 indicates holes in the bottom of the tray 25.

27 indicates a freezing can. 80

28 indicates the cover of the freezing can 27.

29 indicates packing between the can 27 and its cover 28.

30 indicates a pipe communicating between 85 the container 3 and the freezing can 27.

31 indicates a 3-way stop cock in the pipe 30.

32 indicates a pipe communicating between the can 27 and the pipe 7 to the vacuum 90 pump.

33 indicates a 3-way stop cock in the pipe 32.

Referring to Fig. 4, 3' indicates a container similar to container 3. 9' indicates a 95 container similar to container 9. 10', 12', 14', 16' and 18' indicate cylinders within the container 9' and similar to cylinders 10, 12, 14, 16 and 18. 34 indicates an annular shelf secured to the cylinder 16'. 35 indicates an 100 annular shelf secured to the cylinder 12'. 36 indicates an annular shelf secured to the cylindrical container 9'. 37 indicates saw-toothed edges of the shelves 34, 35 and 36.

Having described the principal parts involved in my invention, I will briefly describe the operation of the same.

The water enters through the supply pipe

1 into the interior of the cylinder 18 and then filtering through the filter material 20 passes under the lower edge of the cylinder 18 and up through the filter material 5 between the cylinders 16 and 18. As the water overflows the cylinder 16 it runs into the tray 21 and through the holes 22 thereof into the filter matter between the cylinders 16 and 14. Then the water passes under 10 the lower edge of the cylinder 14, up through the filter material and overflows the cylinder 12 into the tray 23 and through the holes 24 thereof into the filter material between the cylinders 10 and 12. From 15 thence it passes under the lower edge of cylinder 10 and overflows into the tray 25 and through the holes 26 thereof. The holes 26 are so placed as to be over the ledge 3* and as the water drops from the holes 20 onto the ledge any air contained in the water will be separated therefrom and pass off through the vacuum pipe 7. The water then goes down between the containers 3 and 9 and off through the pipe 30 to the 25 freezing can 27. The filtering material 20 may be wood shavings, charcoal or any other suitable material. During the operation a vacuum pump connected to the pipe is 30 kept working and as the air or other gases rise to the top of the filtering material and is liberated by the water dripping through the holes in bottom of the trays and splashing on the ledge 3*, it passes off through the vacuum pump. As the receiving can 27 35 is also connected to the vacuum pump by the pipe 32 no air can become mixed with the water entering it and so the water is kept free of air or other gases. To obtain the best results the water in the container 3 should be kept below the level of the ledge 3* and this is regulated by the stop cocks 2 and 31. The vacuum is regulated by the 40 cocks 8 and 33.

The freezing may take place in the can 45 27 as shown connected to the filtering container or the can 27 may be separated and placed in a freezing chamber and another similar can or other vessel attached to the top 28 which is permanently connected to 50 the filtering container. A permanent vessel with proper inlets and outlets and with vacuum connections may also be placed between the filter container and the freezing can proper.

55 As an alternative construction in place of the trays with holes therein, in the modified construction shown in Fig. 4 the water trickles through the angular notches formed at the base of the saw teeth as through the 60 holes 22, 24 and 26. The saw teeth 37 of the shelf 36 are so placed that the water trickling therethrough will fall on the ledge of the container 3' the same as through holes 26.

65 Hence it will be seen that I have devised

simple means for filtering and removing air, gases and other foreign particles from water before freezing thus insuring a pure clear ice. The water when entering the filter container may or may not have passed 70 through any previous stage of filtering or chemical purification.

What I claim as my invention is:

1. In a filter, the combination with a supply pipe, of a filter container connected therewith, a receptacle connected with the filter container and a vacuum pipe connected with the filter container and with the receptacle. 75

2. In a filter, the combination with a supply pipe, of a filter container connected therewith, and containing filtering material, a receptacle connected with the filter container and a vacuum pipe connected with the filter container and with the receptacle. 80

3. In a filter, the combination with a supply pipe, of a filter container connected therewith, a series of concentric members located one within the other spaced apart, 90 having their upper ends in stepped relation and alternate bases closed to direct the water in a serpentine course to overflow over each alternate step, a receptacle connected with the filter container and a vacuum pipe connected with the filter container and with the receptacle. 95

4. In a filter, the combination with a supply pipe, of a filter container connected therewith, a series of concentric members located one within the other, spaced apart, with their alternate bases closed to direct the flow of water in a serpentine course over each alternate member, means for dividing the flow of water into fine streams 100 as it flows over the members, a receptacle connected with the filter container, and a vacuum pipe connected with the filter container. 105

5. In a filter, the combination with a supply pipe, of a filter container connected therewith, a series of concentric wall members located one within the other, spaced apart with their alternate bases closed to direct the flow of water in a serpentine course over each alternate member, trays 110 extending around and carried by each alternate member and provided with perforations through which the flow of water passes in fine streams, a receptacle connected with the filter container, and a vacuum pipe connected with the filter container. 115

6. In a filter, the combination with a supply pipe, of a filter container connected therewith, a series of endless wall members arranged one within the other spaced apart and having filter material therebetween with their alternate bases closed to direct the flow of water in a serpentine course over each alternate member, annular trays car- 120 125 130

ried by and extending around alternated wall members and provided with perforations through which the flow of water passes in fine streams, a receptacle connected with the filter container, and a vacuum pipe connected with the filter container.

7. In a filter, the combination with a supply pipe, of a filter container connected therewith, a series of wall members arranged within the container, spaced apart, having filter material therebetween with their alternate bases closed to direct the flow of water in a serpentine course over each alternate member, annular trays carried by and extending around alternate wall members and provided with perforations through which the flow of water passes in fine streams, a shelf onto which the water falls carried by and projecting from the container, a receptacle connected with the filter container and a vacuum pipe connected with the filter container.

8. In a filter, the combination with a supply pipe, of a filter container connected therewith, a wall member within the filter container adapted to direct the flow of water thereunder, a wall member within the container adapted to direct the flow of water thereover, means for dividing the flow of water into fine streams as it flows over said wall, a receptacle connected with the filter container and a vacuum pipe connected with the filter container.

9. In a filter, the combination with a supply pipe, of a filter container connected therewith, a wall member within the filter container adapted to direct the flow of water thereunder, a wall member having a bottom within the container adapted to direct the flow of water thereover, means for dividing the flow of water into fine streams as it flows over said wall, a ledge onto which the water falls as it passes from the said dividing means, a receptacle connected with the container and a vacuum pipe connected with the container.

10. In a filter, the combination with a supply pipe, of a filter container connected therewith, a wall member within the filter container adapted to direct the flow of water thereunder, a wall member within the filter container adapted to direct the flow of water thereover, a ledge onto which the water falls

as it flows over said wall, a receptacle connected with the container and a vacuum pipe connected with the container.

11. In a filter, the combination with a supply pipe, of a filter container connected therewith, a wall member within the filter container adapted to direct the flow of water thereunder, a wall member within the filter container adapted to direct the flow of water thereover, a tray provided with perforations adapted to divide the flow of water into fine streams as it flows over said wall member, a receptacle connected with the container and a vacuum pipe connected with the container.

12. In a filter, the combination with a supply pipe, of a filter container connected therewith, a wall member within the filter container adapted to direct the flow of water thereunder, a wall member within the filter container adapted to direct the flow of water thereover, means for dividing the flow of water into fine streams as it flows over said wall, a ledge onto which the water falls and a vacuum pipe connected with the container.

13. In a filter, the combination with a supply pipe, of a container connected therewith, a wall member within the container adapted to direct the flow of water thereover, means for dividing the flow of water into fine streams as it flows over said wall, a ledge onto which the water falls and a vacuum pipe connected with the container.

14. In a filter, the combination with a filter container and inlet therefor, of a receptacle connected with the filter container and a vacuum pipe connected with the filter container and with the receptacle.

15. In a filter, the combination with the supply pipe, of a filter container having its central portion connected therewith, a receptacle connected with the filter container, a vacuum pipe connected both to the filter container and receptacle, and means for directing the flow passing into the filter container radially in all directions and dividing such flow into fine streams as it passes from the center outwardly to the periphery of the container.
